[57] CLAIM

The ornamental design for an article carrier blank, substantially as shown and described.

DESCRIPTION

FIG. 1 is a top plan view of an article carrier blank embodying my new design;

FIG. 2 is a side elevational view looking in the direction of line 2—2 of FIG. 1; and

FIG. 3 is a bottom plan view looking in the direction of line 3—3 of FIG. 2.

The article carrier blank is constructed of material of conventional thickness, and the dashed lines in the drawing represent score lines.
